PATTERN MECHANISM FOR DOBBY LOOMS

John A. Talbert and Maurice Hendrick,
Cliffside, N. C.

Application April 28, 1939, Serial No. 270,587

4 Claims. (Cl. 139—67)

This invention relates to a pattern mechanism for doby looms and more especially to a device of this type which is capable of controlling a fabric pattern which has a plurality of different type weaves therein.

Heretofore, doby looms have been equipped with exceedingly long pattern chains. In many instances, it has been necessary to provide a chain link or bar for each pick in the pattern, even though the weave might repeat itself every third or fourth pick. The cost of constructing and mounting a chain of this length has proved to be excessive. Also due to its length, much mill space is occupied by the chain that might be otherwise used to an advantage.

It is, therefore an object of this invention to provide a pattern mechanism for a doby head comprising a pattern chain having a plurality of linked bars therein for controlling the head, with means for moving the chain forward for a plurality of picks and means for reversing the chain to a previously occupied position in time for it to control the next successive pick. The chain will then move forward again until it is reversed as before. This type of pattern mechanism is particularly important where a repeat weave is being controlled. The reversing of the chain for each repeat, causes the same bars to be used over and over again as long as the repeat weave is woven, thereby shortening pattern chains to a minimum.

It is another object of this invention to provide a pattern mechanism for a doby head which is adapted to control a plurality of different types of weave in a fabric, comprising an endless bar chain with a group of bars therein for each type of weave in the fabric, alternate weaves requiring oscillatory motion of the pattern chain and the other weaves requiring forward motion of the chain.

It is a further object of this invention to provide a pattern mechanism of the class described which is adapted to control not more than two weaves, comprising an endless chain with alternate bars for controlling the first weave and the other bars for controlling the second weave. Means are provided for advancing the chain, step by step, two bars at a time, past the doby fingers to actuate the same and to cause the first weave to be controlled each step by said bars. At the end of the first weave, a suitable reversing means is actuated to reverse the chain one bar, after which the chain is advanced two bars at a time, as before, in a step-by-step manner, but during the second weave, the other bars will control the weave because these bars will be caused to stop beneath the doby fingers upon each step instead of the alternate bars.

The herein disclosed mechanism is particularly adapted for use in the manufacture of crinkle

cloth and towels where a plurality of patterns are used during the weaving of the fabric. However, it is to be understood that the mechanism will be equally effective when used in the manufacture of other type goods, especially if this type goods has a plurality of weaves therein.

Some of the objects of the invention having been stated, other objects will appear as the description proceeds, when taken in connection with the accompanying drawings, in which—

Figure 1 is an end elevation of a doby head with the invention secured thereto;

Figure 2 is a vertical sectional view taken along the line 2—2 in Figure 1 showing the connection between the invention and a conventional box chain;

Figure 3 is an elevation of the rear side of the doby head taken along the line 3—3 in Figure 1;

Figure 4 is a vertical sectional view through the box chain controlling means, taken along line 4—4 in Figure 1, showing the multiplier mechanism;

Figure 5 is a vertical sectional view taken along the line 5—5 in Figure 1;

Figure 6 is a schematic view of a complete pattern chain which is adapted to operate in combination with the invention;

Figure 7 is an isometric view of a fabric woven by the improved pattern mechanism;

Figure 8 is an elevation similar to Figure 3 but showing a slightly modified form of the invention;

Figure 9 is a schematic view showing a complete pattern chain which is adapted to operate in combination with the form of the invention disclosed in Figure 8;

Figure 10 is an isometric view of a fabric, the weaving of which is controlled by the mechanism disclosed in Figures 8 and 9.

Referring more specifically to the drawings, the numeral 10 denotes a suitable supporting bracket, the upper end of which has rotatably mounted therein the shaft 11 upon which a double ended sprocket 12 is mounted. This sprocket has disposed thereon, a conventional box chain 14, comprising a plurality of links 15, joined together by means of transversely disposed pins 16. These pins have sleeves 17 mounted therearound and between these sleeves are disposed suitable rollers 18, 19 and 20. The shaft 11 together with the sprocket 12, is driven in timed relation to the loom. A portion of the loom frame is designated by reference character 21 (Figure 3). As the sprocket rotates, the rollers 18, 19 and 20 are caused to move over the top side of the sprocket and beneath suitable levers 22, 23 and 24, all of which perform functions in the operation of a doby loom. The roller 18, however, which operates lever 22 is an important part of the invention, to which special attention will be given later in the specification.

The chain 14 has half-round rollers 25 secured thereto at the desired points. These rollers are adapted to move beneath the lower end of a lever 26 which is hingedly secured to one end of another lever 27 (Figure 4). Lever 27 is fixedly secured to a shaft 28, which shaft has levers 29 and 30 connected to the other end thereof. The free end of lever 29 is adapted to rest upon multiplier chain 31 on a shaft 32 whereas the free end of lever 30 is adapted to fit in the grooved pulley 33 on the same shaft to engage or disengage the driving means which drives the multiplier chain 31 in a well known manner. These parts are conventional, but it is deemed necessary to disclose this much of the old structure to more clearly describe the present invention. It should be borne in mind, however, that when a roller 25 moves beneath the lever 26 that the box chain 14 will remain in stationary position until the 20 multiplier chain makes one complete revolution, at which time a projection 36 on the chain will move beneath the lever 26 to cause the shaft 11 and box chain to be again set in motion.

The box chain and multiplier just described are 25 adapted to work in conjunction with a dobby head assembly 37. This assembly comprises a pair of side frames 38 and 39 in which is journaled a suitable rocker shaft 40. Secured to the front side of this rocker shaft is an arm 41, the upper 30 end of which is connected to upper dobby knife 43 by means of a link 44. The lower end of arm 41 is similarly connected to lower dobby knife 46 by means of a suitable link 47 (Figure 1). The dobby knives 43 and 46 have their ends mounted 35 in suitable upper and lower slots 48 and 49, respectively (see Figure 3), which slots are disposed in the frames 38 and 39. Connected to the ends of the dobby knives 43 and 46 which extend through the rear side of the dobby assembly, are 40 links 55 and 56, respectively, said links having their other ends connected to the upper and lower ends of a rocker arm 57. This arm is fixedly secured around the rearwardly projecting end of the rocker shaft 40. An extension 58 is 45 an integral part of the rocker arm, which extension projects substantially at right angles therefrom and has a slot 59 therein. Adjustably mounted within this slot is the upper end of a link 60 which is driven from a portion of the loom, 50 not shown. During the operation of the loom, the link 60 is reciprocated up and down to thereby oscillate the shaft 40 and to also cause the upper and lower dobby knives 43 and 46 to reciprocate back and forth in the slots 48 and 49.

Disposed between frames 38 and 39 is a transversely disposed shaft 65 around which the lower end of a plurality of dobby jacks 66 are adapted to pivot. Each of these dobby jacks has a slot 67 near its lower end which fits around another 60 transversely disposed bolt 68. The upper end of each dobby jack has a plurality of notches 69 in which one end of a connecting link 70 is adapted to be fastened. The other end of this link operates a loom harness.

Pivotedly secured to the intermediate portions of the dobby jack 66 as at 72 is a lever 73 (Figure 5). The upper end of this lever has pivoted thereto as at 74, a hook 75, said hook extending to the right in Figure 5, and having its free end disposed above the upper dobby knife 43. The free end of this hook is normally held out of engagement with the reciprocating dobby knife 43 by means of a vertically disposed rod 77, the upper end of which contacts the lower intermediate portion of this hook member. The lower

end of the rod 77 normally rests upon the left-hand end of a dobby finger 78 and this finger is pivoted intermediate its ends upon a transversely disposed shaft 79. The extreme right-hand end of the finger 78 is adapted to rest upon a transversely disposed supporting bar 80 which spans the distance between the side frames 38 and 39.

The lower end of lever 73 has pivoted thereto as at 83 a hook 84, which is similar to hook 75, said hook projecting forwardly and having its right hand end disposed in operative relation to lower reciprocating dobby knife 46. The intermediate portion of hook 83 is adapted to be contacted by the left hand end of a dobby finger 85 which has its intermediate portion pivotally supported by transversely disposed shaft 79. The right hand end of this lever 85 is adapted to be supported by the transversely disposed member 86.

It is evident that when the finger 78 is rotated in a counter-clockwise manner about shaft 79, that the rod 77 will be lowered and at the same time the right hand end of the hook 75 will be lowered to allow the reciprocating dobby knife to engage the hook and thereby rotate the upper end of dobby jack 66 about shaft 68. This movement will raise or lower a harness in the loom to cause the shed to be formed.

Likewise when the right hand end of finger 85 is raised to the position shown in Figure 5, the right hand end of the hook 84 will be lowered into engagement with the lower reciprocating dobby knife 46 and of course this will also allow the knife to rotate the dobby jack about shaft 65 to raise or lower a harness. This is conventional structure in dobby heads.

The fingers 78 and 85 are actuated by a suitable pattern chain 90. This pattern chain comprises a plurality of bars 91, 91a, 91b, 91c, 91d, 91e, 91f and 91g, which are linked together, each bar having two rows of pins, namely, 92 and 93, therein which are adapted to move into engagement with the lower sides of the dobby fingers. The purpose of placing two rows of pins in each bar is to enable one to operate the dobby for two picks each time a bar is advanced to uppermost position. In Figure 5, a pin 92 is shown raising the right hand end of finger 85 to allow the lower hook 84 to be lowered into the path of lower dobby knife 46. In a like manner, the pins 93 50 actuate fingers 78 to lower hooks 75.

Pattern chain 90 is mounted upon a fluted roller 95 on transversely disposed shaft 96, said shaft having its ends journaled in bearings 97 and 98 on the lower portions of the sidewalls 38 and 39, respectively. Fixedly secured upon the rearwardly projecting end of shaft 96 (Figures 1 and 3) is a disk 100 having arcuate notches 101 in the periphery thereof. These notches are adapted to be engaged by a roller 103 on the intermediate portion of downwardly extending lever 104. This lever is rotatably mounted around the rearwardly projecting end of shaft 79 and is normally biased in a counter-clockwise manner in Figure 3 by means of a tension spring 105. The spring 105 holds the roller 103 either in contact with a cavity 106 or against the high portion between these notches on the disk 100. The roller 103 and the disk 100 merely serve to hold the fluted roller 95 and pattern chain 90 in the proper position while two picks are being made by the loom.

The projecting end of shaft 96 also has a sprocket 107 fixedly secured thereon upon which a sprocket chain 108 is mounted. The chain is

also mounted upon a larger sprocket 109 said sprocket being rotatably mounted around stud 110, which stud is mounted in bracket 111 fixed to the sidewall of the dobby head. Secured to the face of sprocket 109 is a ratchet wheel 114, the teeth of which are adapted to be engaged by the projecting end of a hook member 115. This hook projects to the left in Figure 3 and is adjustably secured to a bracket 117 by any suitable means such as set screw 118. It will be noted that the bracket has its left-hand end adjustably and pivotally secured as at 119 within slot 120. This slot is disposed in the lower portion of rocker arm 57. As the arm 57 oscillates back and forth about rocker shaft 40, the right-hand end of hook 115 engages the teeth in ratchet wheel 114 to thereby cause the sprockets 109 and 107 to rotate in a counter-clockwise manner. Due to the position of the hook on the free end 20 of the member 115, and due to the gearing, the shaft 96 and its associated fluted roller 95 is rotated sufficiently to move a bar 91 to upright position for each oscillation of the rocker arm 57. In other words, the loom performs two picks 25 each time the rocker shaft 40 is oscillated; consequently it is necessary to bring bar 91 to upright position beneath the fingers 78 and 85 each time an oscillation is made. The structure described by the reference characters 95 to 115 inclusive 30 might be broadly termed as the means for advancing forwardly the pattern chain 90.

In order to eliminate the necessity of having an excessively long pattern chain, means have been provided whereby the pattern chain will be moved forwardly for a plurality of bars and then means will be employed for returning the chain to a previously occupied position during one half of an oscillation of the rocker shaft 40 to thereby position the bars so that they can be used over again. This restoring mechanism comprises a ratchet wheel 125, the lower portion of which is adapted to be engaged at times by the hook on the end of member 126, said ratchet being an integral part of sprocket 109. The member 126 is adjustably mounted in bracket 117 by means of set screw 127. When a predetermined number of bars 91 have been rotated beneath the fingers 78 and 85, the free end of hook 126 is moved upwardly into engagement with the teeth in ratchet wheel 125 and then upon the clockwise oscillation of rocker arm 57 and crank shaft 40, the reverse rotation will be effected upon the sprockets 109 and 107 and also upon shaft 96, roller 95 and pattern chain 90 to cause the chain to be restored to a preoccupied position. Due to the mechanical structure and arrangement of hooks 115, and 126, and their associated ratchets, the pattern chain may be moved forwardly by hook 115, one bar for each oscillation of the rocker arm, whereas it may be reversed two bars upon each oscillation when hook 126 is in engagement. After this restoring has taken place the member 115 and its associated hook is adapted to again assume the position as shown in Figure 3 at which time the chain 90 will again resume its forward or counter-clockwise rotation.

The means for causing the hook on the end of member 126 to engage the ratchet wheel 125, however, will now be described. It will be noted that the intermediate portion of hook 115 has connected thereto a tension spring 128, and the upper end of this tension spring is secured to the free end of a lever 129, said spring acting 75 as a resilient link (Figure 3). Lever 129 is piv-

oted as at 130 in slot 131 of bracket 132. Disposed on the lower intermediate portion of this lever is a cam surface 133, said cam surface being adapted to be contacted at times by laterally projecting pins 134 and 135 which project from the inner face of a ratchet wheel 136. This ratchet wheel is rotatably mounted around stud 137 which likewise is secured to bracket 132. The teeth in the ratchet 136 are engaged by the hook on the free end of a member 138, said member 10 having its left-hand end (Figure 3) pivoted as at 139 in slot 140. This slot is cut in the upper portion of rocker arm 57. A torsion spring 141 normally tends to hold the free end of hook member 138 into engagement with the teeth of 15 ratchet 136.

It is seen that as the rocker arm 57 and the rocker shaft 40 oscillate that the ratchet 136 will be advanced notch by notch, that is the ratchet will be advanced one notch for each 20 complete oscillation of the rocker arm. In order to hold the ratchet wheel 136 in the position during the operation of the hooked member 138, a suitable roller 145 has been disposed intermediate the ends of a lever 146, said lever being pivoted as at 130 to bracket 132. The free end of the lever 146 normally is pulled in a counter-clockwise manner about point 130 by means of a tension spring 148. This spring holds the roller 145 in one of a plurality of arcuate notches 25 150 which are disposed in the periphery of a disk 151, said disk being fixedly secured to the face of ratchet wheel 136.

It can be seen by referring to Figure 3 that each time the right-hand end of hook member 35 138 makes a complete oscillation that the mechanism previously described will operate to bring another bar 91 to uppermost position upon the fluted roller 95 and in operative rotation with fingers 78 and 85.

Since there are two pins 134 and 135 disposed in the face of ratchet 136, and since there are only six notches in the periphery thereof, it is also evident that only three bars can be advanced before one of the pins 134 or 135 will rise beneath the cam surface 133 of lever 129 to cause the same to be raised. When this lever is raised the lower hook member 126 will be drawn into engagement with the ratchet wheel 125, and subsequently when the rocker arm is oscillated in 50 a clockwise direction (Figure 3) the chain 90 will be reversed a distance of two bars and be restored to original position. In other words, when the hook member 115 is disposed in its extreme right-hand position in Figure 8, with its 55 free hooked end in engaging position with ratchet 114, the hook will be disposed a slight distance to the right of the teeth in this ratchet; consequently, when the rocker arm oscillates to the left the hook will travel a short distance to the 60 left before engaging the teeth to rotate the same. The hook on the end of member 126 is so positioned that it will engage the teeth to rotate ratchet 125 immediately upon oscillation of 65 rocker arm to the left, that is when the hook member is raised to engaging position. There is no lost motion between the hook member 115 and the teeth in ratchet 125. Of course when one of the pins 134 or 135 rides out from beneath the cam surface 133 upon the next oscillation of 70 the rocker arm, the hook 115 will fall again into engagement with its ratchet wheel 114 to cause the forward motion of pattern chain 90 to be again effected. The above described mechanism is operated in the manner stated where a repeat 75

weave is being made in a cloth. In the present instance three different bars are moved into engaging relation with dobby fingers 78 and 85. Then the bars are reversed to original position 5 to allow these same bars to be used over again and again. Since each bar represents two loom picks, it naturally follows the following set-up is made for six pick repeats.

Where it is necessary to transfer from a repeat 10 weave into another type of weave then the reversing process of the chain must be rendered inoperative and forward motion only imparted to the chain 90 while this extra weave is being made. In order to render inoperative this reverse motion, it is necessary to lift the hook member 138 out of engagement with ratchet 136. This lifting is effected by an inwardly and laterally projecting end 155 which is disposed beneath the intermediate portion of member 138, 15 and which forms an integral part of a lever 156. Lever 156 has its intermediate portion mounted for oscillation around stud 137. The lever 156 also projects a substantial distance to the right of stud 137 and has the upper end of a link 158 20 secured thereto, the lower end of which is pivotally secured to the upwardly extending end of lever 22 previously described (Figures 1, 2 and 3). Upon the completion of the repeat weave, if it is desired to continue the forward rotation of 25 the chain in one direction only, a ball 18 (see Figures 1 and 2) will ride beneath the lowermost end of lever 22 to cause the same to be rotated in a clockwise manner in Figure 2. This will rotate the lever 156 in a clockwise manner in Figure 3 30 to cause the inwardly projecting end 155 to be moved beneath the intermediate portion of hooked lever 138 and lift its hook out of engagement with ratchet 136. A torsion spring 160 is provided for normally rotating the lever 156 in a counter-clockwise manner to the position 35 shown in Figure 3. As long as the roller 18 remains beneath the end of lever 22 only forward motion can be imparted to the pattern chain because a pin 134 or 135 cannot be moved beneath the cam surface 133 of lever 129 to cause the free end of said lever to lift reversing hook 126 into engagement with ratchet 125. During this forward motion of the chain 90 the hook on the end of member 115 will be engaging the 40 teeth in ratchet 114 and thus advancing one bar 91 for each oscillation of the rocker arm.

Let us suppose that it is desired to weave a towel such as shown in Figure 7 which is designated by reference character 162. Within this 45 towel there are three different kinds of weaves, namely, the reverse terry weave 163 on each end thereof, border weave 164, regular terry weave 165 and another border 166. Assuming that we are beginning at the near end of the towel as shown in Figure 7 in the reverse terry weave 163. At this time the bar 91 will remain beneath the fingers 78 and 85 for two picks; then the next bar 91a will move to uppermost operative position and remain there for two picks and then a bar 91b will move to the uppermost position and remain for the same length of time. At this time, the bars will be restored to the position shown in Figure 6 by means of restoring hook 126 in Figure 6 previously described. The restoration 50 takes place between picks. This step-by-step forward motion of the chain and the one step restoring motion will be repeated until the border 164 is reached, after which a roller 18 will move beneath the lower end of lever 22 to cause the lever 156 (Figure 3) to disengage the hook mem-

ber 136. Then the chain will continue its forward motion over twelve successive bars 91c, representing twenty-four picks which will be disposed within this border portion. At this time the roller 18 will be caused to move from beneath the lower end of lever 22 at which time the bars 91d, 91e and 91f will move back and forth beneath the fingers 78 and 85, during the weaving of regular terry portion 165 in the same manner that the bars 91, 91a and 91b moved while the reverse terry was being woven. Upon the completion of the regular terry 165 another border 166 is woven by twelve successive bars 91g in the same manner that the bars 91c were used to weave the previous border 164, and upon the completion of the border, the reverse terry portion 163 on the far end of the towel will be woven in the same manner previously described.

Figures 8, 9 and 10 show a modified form of the invention which is employed for weaving a fabric having not more than two types of weaves. Figure 10 shows a towel 175 having a terry weave 176 on each end thereof as well as a terry weave 176 disposed between two border weaves 177. An especially constructed pattern chain 178 is 20 employed for weaving this type of fabric. This pattern chain comprises a plurality of alternately spaced bars 179 and a plurality of alternately spaced bars 180, each having pins 92 and 93 therein for operating dobby fingers 78 and 85. The bars 179 are adapted to control the mechanism for weaving the terry weaves 176 whereas the bars 180 are adapted to control the border weaves 177. Therefore, when the terry weave 176 is being woven, it is necessary to rotate 25 the fluted roller 95 for a distance equal to two links of the chain for every two loom picks. By doing so, then a link 179 will be disposed in the uppermost operative position upon each oscillation of the rocker arm 57. When the terry weave has been completed and it is desired to weave a border area 177, it is then necessary to provide means for reversing the chain a distance of one link so that a bar 180 will be disposed in uppermost position and beneath the 30 fingers 78 and 85. After this is done the chain will resume its normal forward movement with each movement of the chain being equal to two bars. Therefore, only the alternate bars 180 will stop beneath the fingers 78 and 85 until the chain 35 is again reversed for an odd number of bars.

The structure used for moving the chain 178 a distance of two bars when the terry weave 176 is being woven is similar to that in the preceding form. Revision is made in hook members 185 and 187 and also the point 119, where the bracket 117 is secured to the lower end of the rocker arm, has been lowered, thereby giving the hooked member 185 a greater throw. Consequently, the oscillation of the rocker arm 57 will cause the hook on the end of arm 185 to advance the ratchet 114 two notches instead of one, as in the preceding form. This, in turn, will cause the fluted roller 95 to advance the chain 176 two bars. Adjustably secured to the bracket 117 is another hook 187 which is similar to the hooked member 126 as shown in Figure 3. This hooked member has been lengthened considerably and so positioned that upon the oscillation of the rocker arm 57 and upon the engagement 40 of the hook on this member with the ratchet 125 that this ratchet will only be reversed one notch instead of two as in the preceding form. In other words, when hook member 187 is disposed in its extreme right hand position in Fig- 45

ure 8 with its free hooked end moved up into engaging position, this hook will be disposed a slight distance to the right of the teeth in ratchet 125; consequently when the rocker arm oscillates to the left the hook will travel a short distance to the left before engaging the ratchet to rotate the same. The reversal of the ratchet as heretofore stated is effected when a transfer is desired to be made from the terry weave to the border weave or vice versa.

In order to throw the hooked end of member 187 into engagement with ratchet 125 at the proper time, a roller 18 of box chain 14 such as illustrated in Figures 1 and 2 is caused to be moved beneath the lower end of arm 22 at the proper time. The lever 22 will then be rotated in a clockwise manner in Figure 2, which, in turn, will cause the lever 156 to rotate in a clockwise manner in Figure 8. This motion of lever 156 will be transmitted to bracket 117 and the hook member 187 through a spring link 128a. The assembly comprising members 117, 185 and 187 will be rotated in a counter-clockwise movement about pivot point 119 to cause the hook on the end of member 187 to engage the ratchet 125. Special attention is called to the fact that the upper hook 185 is so positioned that it will pull the chains 118 forwardly the distance of two bars for each oscillation of the rocker shaft; whereas the lower hooked member 187, when it is caused to engage with its ratchet, will reverse the chain only one link for each oscillation of the rocker shaft.

In the drawings and specification, there has been set forth a preferred embodiment of the invention and although specific terms are employed, they are used in a generic and descriptive sense only and not for the purpose of limitation, the scope of the invention being set forth in the appended claims.

We claim:

1. A pattern mechanism for a loom dobby head having dobby fingers for controlling the weaving of a fabric and also having a rocker arm for the operation of said head, comprising a roller disposed below said fingers, a pattern chain having a plurality of linked bars therein disposed on said roller with the uppermost bar normally in engagement with the fingers, a ratchet operatively connected to said roller for driving the pattern chain in one direction, a second ratchet operatively connected to said roller for driving the pattern chain in the opposite direction, a pawl for each of said ratchets and being driven by said rocker arm, the pawl for said first ratchet being normally engaged to rotate the pattern chain forwardly upon each oscillation of the rocker arm and the pawl for said second ratchet being normally disengaged, a box chain and means controlled by said box chain for disengaging said first pawl and engaging said second pawl with their respective ratchets to cause the pattern chain to rotate reversely, the pawls engaging their respective ratchets at different points in their stroke to thereby rotate the ratchets different amounts.

2. A pattern mechanism for a loom dobby head having dobby fingers for controlling the weaving of a fabric and also having a rocker arm for the operation of said head, comprising a roller disposed below said fingers, a pattern chain having

a plurality of linked bars therein disposed on said roller with the uppermost bar normally in engagement with the fingers, a ratchet operatively connected to said roller for driving the pattern chain in one direction, a second ratchet operatively connected to said roller for driving the pattern chain in one direction, a pawl for each of said ratchets and being driven by said rocker arm, the pawl for said first ratchet having an effective stroke while engaging its ratchet to 10 advance the pattern chain forwardly upon each oscillation of the rocker arm a predetermined distance and the pawl for said second ratchet having an effective stroke while engaging its ratchet to reverse the pattern chain a distance 15 differing from the amount of forward movement of the first ratchet, a box chain, means controlled by said box chain for disengaging said first pawl and engaging said second pawl with their respective ratchets to cause the pattern 20 chain to rotate reversely, and means for restoring said pawls to normal position after said reversal has been effected to cause the pattern chain to again resume its forward rotation.

3. In a dobby head for looms having dobby fingers, dobby knives, jacks and a rocker arm operatively connected to the dobby knives for imparting reciprocating motion thereto, a roller having a pattern chain mounted thereon, a box chain, a pair of ratchet wheels operatively connected to the roller for driving the same, a pair of pawls rigidly connected to each other and pivotally mounted at one end of the rocker arm, means normally holding one of the pawls in engagement with one of the ratchet wheels for 30 advancing the roller and its pattern chain in one direction, operative connections between the box chain and said pawls for shifting the position of said pawls relative to the ratchet wheels to cause the other of said pawls to engage its 35 associated ratchet wheel upon oscillation of the rocker arm to impart reverse rotation to the pattern chain, the effective stroke of the two pawls on their ratchets being different to cause the 40 amount of advance and reverse of the pattern 45 chain to differ from each other.

4. In a dobby head for looms having dobby fingers, dobby knives, jacks and a rocker arm operatively connected to the dobby knives for imparting reciprocating motion thereto, a roller having a pattern chain mounted thereon, a box chain, a ratchet wheel operatively connected to the roller, a member pivotally mounted on the rocker arm and having a pair of pawls projecting therefrom and being disposed on opposed sides of the ratchet wheel, means for normally holding one of the pawls in a position to rotate the ratchet wheel in one direction upon oscillation of the rocker arm, a box chain and operative connections between the box chain and said pawls for 50 shifting the position of the pawls to cause the other of said pawls to engage the ratchet wheel upon oscillation of the rocker arm to drive the ratchet wheel and the roller in a reverse direction, the effective stroke of the two pawls on their 55 ratchets being different to cause the amount of advance and reverse of the pattern chain to differ from each other.

JOHN A. TALBERT.

MAURICE HENDRICK. 70
